CUSHIONING DEVICE

Lloyd B. Jones, Hollidaysburg, Pa., assignor to
The Pennsylvania Railroad Company, Philadelphia, Pa., a corporation of Pennsylvania

Application September 27, 1941, Serial No. 412,615

11 Claims. (Cl. 238—283)

This invention relates to cushioning devices for absorbing shocks imparted to supported elements such for example as track rails or car bodies, or to elements subjected to sudden movement or jars from different directions such for example as the draft gears of railway cars.

One of the aims of my invention is to make it possible to cushion and absorb shocks gently but effectively in progressive stages graduated in proportion to the magnitude of the impulses. This objective I attain in practice as herein-after more fully disclosed, through provision of a cushioning device having opposed groups of load supporting or pressure elements between which resilient elements of rubber or the like are interposed, and by the cooperative action of which the intervening resilient elements are initially subjected to compression and afterwards to shearing action as the load increases.

Other objects and attendant advantages will appear from the following detailed description of the attached drawings, wherein Fig. 1 is a fragmentary view in plan illustrating a cushioning device according to my invention in a suitable form for use in interposition between a railway track rail and its supporting tie, portions in the figure being shown in section and others having been broken away to expose important details which would otherwise be hidden.

Fig. 2 is an end elevation of the organization featured in Fig. 1 with the rail shown in cross section.

Figs. 3 and 4 are perspective views of two of the components of the cushioning device.

Fig. 5 is a view in top plan of an alternative form of my improved cushioning device; and

Fig. 6 is an axial sectional view of the modified device taken as indicated by the angled arrows VI—VI in Fig. 5.

With reference first to Figs. 1—4 of the illustrations, 1 designates the railway tie, 2 the tie plate, and 3 the track rail. The cushioning device of my invention by which the rail 3 is directly supported, includes two opposing groups of rigid metallic bar components 5 and 6 in parallel, which may be cast or which may be cut from rolled bar stock of T shaped cross section, the upright webs and head flanges of said components being designated 7, 8 and 9, 10 respectively. Included in the two groups are end bars 11 and 12 of L shaped cross section respectively with upright legs 13, 14 and lateral flanges 15, 16. As shown, the bar components 6 and 12 of the second group are arranged in invert relation to the bar components 5 and 11 of the first group, with the head flanges of adjacent bars in the two groups spaced to receive between them the vertical webs of the other group. It is to be noted that the vertical webs 7 and 8 of the bar components 5 and 6 are

roughened on opposite sides, and the vertical legs 13 and 14 of the end components 11 and 12 are roughened only on their inner sides, the roughening being preferably formed by corrugations which extend in the direction of the length of the bars, i. e., in parallelism with their lateral flanges as best shown in Figs. 1 and 3. The cushioning device further includes a series of resilient components 17 of rubber or the like which may be either separately molded or cut from strip rubber or the like of relatively thin rectangular cross section with smooth side and end faces (see Fig. 4), said strips being of a height somewhat less than that of the upright webs 7 and 8 of the bars and positioned between the opposing roughened side faces of adjacent bars of the two groups. It is to be further noted from Fig. 2 that in accordance with my invention the tie plate 2 is provided with a relatively deep recess 18 between upstanding flanges 19, said recess being slightly wider than the base of the rail 3 and snugly accommodating the bar and strip components as clearly shown. Thus, the elements 5, 6, 17 and the tie plate together constitute a cushioning unit which may be assembled at the time of manufacture and placed as such when the rail is laid. The rail 3 is held in place after a more or less common practice by means of spikes 20 which pass through the tie plate 2 and engage into the tie 1, and have their heads overlapping the opposite flange edges of the said rail. The tie plate 2 is in turn secured to the tie 1 by means of nuts 21 engaging the protruding threaded ends of bolts 22 passing through the tie. As the rail 3 is loaded by passage of trains thereover, it will be seen that the bar components 5 and 11 will move downward relative to the bearing components 6 and 12, such movement being attended initially by compression of the rubber. As the movement continues with incidental lateral expansion of the resilient strips 17, the latter will be eventually gripped by the roughened opposing surfaces of adjacent bar components of the two groups and the strips placed in shear with consequent increase in its resistivity. In this way it will be seen that the vibrations imparted to the rail as it is overtravelled by the trains will be effectively absorbed to the advantage not only of minimizing wear and tear on the rails and ties, but of reducing the noises attending train travels. Since, as shown in Fig. 1, the length of the bar and strip components 5, 6 and 17 corresponds substantially to the width of the tie 1 and aggregate the width of rail base, the rail is afforded full support over the usual area by the cushioning device.

In Figs. 5 and 6 I have shown a cushioning unit which functions in the same manner as

that previously described, but in which the component elements are all annular in form, and one disposed within another. In this form of my invention there are pressure rings 5c and 6c, the latter of which is inverted with respect to the first mentioned, said rings being of T shaped cross section like the bars of the first described embodiment.

Associated with the ring 6c is a ring 12c of L shaped cross section like the ring 12 of the first described embodiment; and interposed between the corrugated upright webs 1c, 8c and 14c of the elements 5c, 6c and 12c are rings 17c of resilient material with a rectangular cross section like that of the strips 17 of the first described embodiment. In addition to the rings 5c and 6c there is a central element 50 which may be regarded as associated with the ring 5c, said central element having a circular head 51 to engage over the top edge of the innermost of the resilient rings 17c, and a corrugated shank 52 whereof the surface opposes the contiguous annular corrugated surface of the ring 6c, the several components above described being all contained in a cuplike housing 52 as shown in Fig. 6. If desired, the elements 5c, 6c and 12c of the device in Figs. 5 and 10 may be cast or they may be produced from cut lengths of T and L shaped bar metal and then bent into circular form with the ends of such lengths abutting as indicated by the radial lines at 55, 56 and 57 in Fig. 5. It is to be understood that I am not limited to the precise number of ring components shown in Figs. 5 and 6, since the number may be increased if necessary to meet special requirements of practice. The alternative embodiment of Figs. 5 and 6 may be used in instances where the square type of units shown in previous forms would be impractical or undesirable, for example, in interposition between the bodies and chassis frames of automobiles and motor trucks, or between the engines and the chassis frames of such vehicles.

Having thus described my invention, I claim:

1. A cushioning device comprising at least two relatively movable reversely arranged pressure components of rigid material with opposing ledges at right angles to opposing roughened surfaces which latter are aligned in the direction of movement of said components; and a resilient smooth surfaced component of rubber or the like interposed between the roughened surfaces of the pressure components with its ends overlapped respectively by and engaging the ledges of the latter components and contacting normally with the high spots only of said roughened surfaces, whereby, incident to movement of the pressure components toward each other under load, the resilient component is first compressed, and afterwards through attendant lateral expansion thereof, caused to be gripped by the opposing roughened surfaces of said pressure components.

2. A cushioning device characterized as in claim 1, wherein the resilient component is relatively thin and flat; and wherein the flat sides of said component are gripped by the opposing roughened surfaces of the pressure components after the initial compression of said resilient component.

3. A cushioning device characterized as in claim 1, wherein the pressure components are in the form of corrugated bars arranged in par-

allel relation and having lateral flanges which provide the ledges; and wherein the resilient component is in the form of a straight bar of rectangular cross section.

4. A cushioning device characterized as in claim 1, wherein the roughening on the opposing faces of the pressure components is provided by corrugations extending parallel to the plane of the ledges of said pressure components.

5. A cushioning device according to claim 1, having plural reversely arranged pressure components; and pressure transmitting plate interposed between adjacent pressure components.

6. A cushioning device characterized as in claim 1, wherein the several components are of annular configuration arranged one within another.

7. A cushioning device characterized as in claim 1, wherein the several components are of annular configuration arranged one within another; and wherein the resilient component is relatively thin and flat sided; and wherein the flat sides of said resilient component are gripped by the opposing roughened surfaces of the pressure components after initial compression of said resilient component.

8. A cushioning device characterized as in claim 1, wherein the pressure components are fashioned into annular form from straight bar stock with lateral ledge means along one edge; and wherein the resilient component is fashioned into ring form from flat-sided strip material of plain rectangular cross section.

9. A cushioning device characterized as in claim 1, wherein the several components are of annular configuration arranged one within another; and wherein the roughening on the opposing faces of the pressure components is provided by annular corrugations which extend parallel to the plane of the ledges on said pressure components.

10. A cushioning device for interposition between track rails and their supporting ties comprising a group of rigid pressure bar components of T shaped cross section laid side by side with another group of alternate pressure bar components inverted relative to the others, the upright webs of the bars having their faces roughened; smooth faced resilient strip components of rubber or the like positioned snug between the vertical webs of the respective bars with their upper and lower edges overlapped by and respectively engaging the head flanges of adjacent bars and contacting normally with the high spots only of said roughened surfaces, whereby, incident to relative movement of the bars under load, the resilient strip components are first compressed, and, through attendant lateral expansion with increase in the load, caused to be later gripped by the opposing roughened faces of adjacent bar components of the two groups; and means for resisting the lateral thrust upon the bar components developed by the lateral expansion of the rubber strips.

11. A cushioning device in accordance with claim 10, in which the thrust resisting means is in the form of a plate with upstanding flanges between which the pressure bar and strip components of the device are confined in assembled relation.

LLOYD B. JONES.
